UNITED STATES PATENT OFFICE.

JOHN POHL, OF BLOOMFIELD, NEW JERSEY.

MEANS FOR BALANCING CENTRIFUGAL BOWLS.

989,043.

Specification of Letters Patent. Patented Apr. 11, 1911.

Application filed January 18, 1910. Serial No. 538,667.

To all whom it may concern:

Be it known that I, JOHN POHL, a subject of the Czar of Russia, residing at Bloomfield, in the county of Essex and State of New Jersey, have invented certain Improvements in Means for Balancing Centrifugal Bowls, of which the following is a specification.

This invention relates to the art of balancing bodies or members which in use are to rotate at high speed, and more particularly the rotary portions of centrifugal machines, such as the bowls of cream separators, for example, which in use rotate at the rate of ten or twelve thousand revolutions per minute. The common method of balancing heretofore in use has been to rotate the bowl or member and from its irregular motion determine the circumferentially light points; then apply additional weight, by solder or the like, to the inside of the bowl at such light points and test again, until the bowl or member rotates evenly.

The objects of the present invention are to enable the compensating weights to be removably applied to the outside of the rotary member being balanced, until its perfect balance is attained, and then permanently secured upon the inside of said member; to thus save much time and labor, and reduce the cost of balancing; to provide means for removably applying weights to any circumferential point of the outside of the rotary member being balanced, and to obtain other advantages and results as may be brought out in the following description.

Referring to the accompanying drawings, in which like numerals of reference indicate corresponding parts in each of the several figures, Figure 1 shows in side elevation the rotary bowl or member of a centrifugal cream separator being balanced by my improved method; Fig. 2 is an enlarged view of one of the weights employed in carrying out my invention; Fig. 3 is a plan of the ring shown at about the middle part of the bowl in Fig. 1, and illustrating one form of construction; Fig. 4 is a section of the same on line 4-4 of Fig. 3; Fig. 5 is a plan of the ring shown at the lower part of the bowl in Fig. 1, said ring being of the preferred construction, and Fig. 6 is a cross section taken on line 6-6 of Fig. 5.

In said drawings, and particularly Fig. 1, 10 indicates the bowl of a centrifugal cream separator, having the spindle 11 provided

with worm 12 adapted to be engaged by worm wheel 13 to rapidly rotate the bowl in bearings (not shown) of any suitable and well-known construction. It will be understood that while I have employed such a bowl to illustrate my invention, it is only illustrative of any body or member which is intended to be rotated at high speed, and therefore must be balanced. There are many 60 centrifugal machines having such bodies or members, and my invention is especially applicable to them.

In carrying out my improved method of balancing the bowl 10, I secure to the bowl 70 a member which provides a circumferential series of seats or sockets in a plane substantially at right angles to the axis of rotation of the bowl. More than one of these members can be employed if desired, and in 75 practice I find it advantageous in balancing cream separator bowls to employ three, one at the top, one at the bottom, and one half way between. It will be understood, however, that the use of any one member embodies the features of my invention. These members may be of any desired detail construction and secured to the bowl or rotary body in any suitable manner, either upon 80 its outside or inside, but for purposes of 85 illustration I have shown them as rings fitting around the cream separator bowl 10 and adapted to be made fast thereon by set screws 17 or 27 working radially through the rings.

The ring 14 which I have shown upon the middle portion of the bowl, has at its upper side an inner shoulder 15 which engages the beveled upper portion 101 of the bowl to hold the ring against dropping downward. Said ring has transverse to its plane a series 90 of holes or sockets 16.

The ring 24 which I have shown at the lower part of the bowl 10 differs in having no inner shoulder, but a uniform cylindrical interior, and obviously such shoulder is not an essential feature of the invention. The sockets or seats 26 in the ring 24 are furthermore not holes arranged midway between the inner and outer sides of the ring, but are 100 recesses or grooves in the inner wall of the ring, as clearly shown in Figs. 5 and 6. This construction of sockets or seats enables them to be located closer to the side of the bowl 105 or other rotary body to be balanced.

The seats or sockets in the members which are to be secured to the rotary body to be 110

- balanced are adapted to removably receive a weight or weights, which may be of any desired form of construction adapted to be retained in said seats or sockets during rotation of the rotary body and at a substantially fixed radial distance from the axis of rotation of the said body. These weights are preferably formed of lead or solder, and for purposes of illustration I have shown them in the drawing as U-shaped and made out of round wire so that the legs 18, 18 of the weight 19 can be inserted in the sockets or seats of the member secured to the rotary body.
- 15 In carrying out my improved method of balancing, one of the members providing a circumferential series of seats or sockets is applied to the rotary body, and then said body is caused to revolve at a high rate of speed. The operator locates the light portion to the best of his ability and inserts a weight in the said member at such light point. He then revolves the rotary body again, and by changing the position of the weight and substituting larger or smaller weights, if necessary, he quickly and accurately secures a true balance. He then marks upon the outside of the bowl the location of the weights which he has applied, and removing the weights and their carrying member from the rotary body, he permanently affixes the weights thereto, as by soldering. In the case of centrifugal separator bowls, the weights are permanently secured to the inside of the bowl preferably, and in doing this proper allowance is made for the difference of radial distance.
- It will be apparent to those having mechanical skill that various modifications can be made in the detail construction of my improved means for balancing, without departing from the spirit and scope of my invention, and I wish to be understood as not limiting myself by positive descriptive terms herein employed, except as the state of the art may require.
- Having thus described the invention what I claim is—
1. The combination with a rotary body, and means for rotating said body upon a vertical axis, of a member removably secured to said rotary body to rotate there-
  - with and providing a series of sockets concentric with said rotary body, and a weight adapted to be mounted in said sockets at different points of the said series.
  2. The combination with a rotary body, and means for rotating said body upon a vertical axis, of a ring removably secured to said rotary body to turn therewith and providing a circumferential series of sockets, and a weight adapted to be mounted in said sockets at different points of the circumference of said member.
  3. The combination with a rotary body and means for rotating said body upon a vertical axis, of a ring removably made fast to the outside of said rotary body and having in itself substantially perpendicular to its plane an annular series of seats or sockets concentric with said rotary body, and a weight adapted to be removably inserted in said seats or sockets.
  4. A device for balancing rotary bodies, comprising a ring having in its inner wall a series of transverse grooves, means for holding said ring in place on a rotary body, and a weight adapted to be removably inserted in said seats or sockets.
  5. The combination with a rotary body having a cylindrical portion, and means for rotating said body upon a vertical axis, of a ring removably secured to said rotary body to turn therewith, said ring providing a circumferential series of sockets and having an inner shoulder overlying the upper end of said cylindrical portion, and a weight adapted to be mounted in said sockets at different points of the circumference of said member.
  6. The combination with a rotary body, and means for rotating said body upon a vertical axis, of a member removably secured to said rotary body to rotate therewith and providing a series of sockets concentric with said rotary body, and a U-shaped weight whose arms are adapted to enter two of said sockets simultaneously at different points of the said series.

JOHN POHL.
